Primary Examiner — Natasha Vujcic

(57) **CLAIM**

The ornamental design for a lamp base as shown and described.

DESCRIPTION

1. Lamp base
2. Lamp base
- 1.1 : Top perspective view of the article
- 1.2 : Top plan view
- 1.3 : Bottom plan view
- 1.4 : Front elevation view
- 1.5 : Rear elevation view
- 1.6 : Right-side view
- 1.7 : Left-side view
- 1.8 : Top perspective view showing the environment
- 2.1 : Top perspective view of the article
- 2.2 : Top plan view
- 2.3 : Bottom plan view
- 2.4 : Front elevation view
- 2.5 : Rear elevation view
- 2.6 : Right-side view
- 2.7 : Left-side view
- 2.8 : Top perspective view showing the environment

The characteristics of the designs are the visual features of the articles as shown in the accompanying drawings; the broken lines in the drawings do not form part of the designs.
